PULVERIZING UNIT

Ralph M. Hardgrove, Westfield, N. J., assignor, by
mesne assignments, to The Babcock & Wilcox
Company, Newark, N. J., a corporation of New
Jersey

Application November 16, 1931, Serial No. 575,317

12 Claims. (Cl. 83—45)

This invention is a pulverizing unit which includes a pulverizer, and a blower and material feeder therefor, together with a unitary driving means thereby maintaining a ratio of air and material never in excess of the capacity of the pulverizer.

In pulverizers of the type including a stationary and movable ring, with rolling elements therebetween, it has been customary to mount the driving mechanism below the pulverizing mechanism with the consequent disadvantage of considerably elevating the stationary pulverizing ring above what could otherwise be the natural foundation level of the total assembly. Thus the construction is expensive in that the component parts have to be heavier than would be necessary were the stationary pulverizing ring not elevated above the driving mechanism. Furthermore such a construction brings the material entrance and pulverulent particle exit higher than is convenient for the usual location with respect to auxiliary equipment. The present invention considerably lessens the weight and expense incident to this type of equipment by bringing the stationary ring down to the level of the natural foundation. According to the present invention the driving mechanism is placed at the top, and incidental thereto, but of equal importance, the present invention also makes possible a reduction in the height at which the material is fed and the pulverulent particles taken off, thereby rendering the pulverizer more compact and easier to install in connection with auxiliary equipment. This is of great advantage from the economic standpoint.

Previously it has been the practice, incident to driving from the bottom to carry the total pressure due to grinding pressure adjustment and the weight of the parts upon a vertical shaft having its total thrust absorbed upon an end thrust bearing. When using the inverted or top drive forming a part of the present invention the driving mechanism is free of the weight of the movable grinding ring, together with its adjustment parts and intermediate driving element, and the thrust bearing absorbs only the thrust of the grinding adjustment as reduced by the weight of the parts mentioned. This construction is thus another feature of the invention.

Current practice, up to the time of this invention, has been to introduce the material to be pulverized downwardly and inwardly between and among rollers separating two ring members, and to distribute the air sweeping blast upwardly and centrally of the pulverizing rings. This has a

tendency to prevent easy entrance of some of the coarse particles to the grinding zone. A construction in accordance with the present invention not only introduces the material to be pulverized annularly and inwardly from the peripheries of the grinding rings between the same and among the roller elements, but also assists the coarser particles in entering between the rollers separating the two ring members by reason of an arrangement which introduces the air sweeping blast in the same direction as the material, to wit: inwardly from the external peripheries of the grinding rings between the same and among the roller elements and sweeping therewith the finely divided or pulverulent particles and thence carrying the same upwardly beyond the grinding elements and out at the top of the enclosing casing. Thus the air travel is over the same path as the material travel, and the air assists the movement of material as it is being fed to the grinding elements.

The present invention also contemplates a vertical pulverizer with an arrangement of a stationary grinding ring in combination with a floating movable grinding ring and a driving mechanism therefor. This includes a floating driving connection which permits the floating grinding ring and the floating driving connection to have free relative displacement with respect to each other, and to the main driving mechanism, thereby relieving the latter of an appreciable amount of strain and consequent wear. This contributes to longer life of the unit and reduced power consumption, and thereby materially decreases the cost per ton of material operated upon.

Sealing means to protect the driving shaft and bearing parts against the abrasive action of the pulverulent particles is another feature of pulverizing units that has presented considerable difficulty, and this present invention again contributes to lessened depreciation and overall upkeep cost by utilizing the air from the blower that furnishes the air sweeping blast to accomplish this function. This is accomplished in a particularly novel way in that the shaft is surrounded by a sealing pocket into which air is introduced by the same blower furnishing air to the enclosing casing of the pulverizer, as above stated. However the parts are so arranged with respect to each other that the velocity component of the air blast is translated into an always greater pressure component than the total pressure existing in the pulverizer casing, and thus air may always escape around the shaft

and into the pulverizer casing thereby effectively excluding dust particles and reducing wear to as absolute minimum in so far as the bearing parts of the driving mechanism are concerned.

5 A further feature of the invention is the provision of an adjustable skirt dividing the material feeding area from the air blast entrance area and thus providing means for regulating the air velocity in the zone adjacent the grinding elements.

10 Additionally, the invention contemplates a table feeder including a rotary disc receiving and moving the material into the pulverizing casing. The amount of material entering the apparatus 15 is controlled by a valve actuatable along the active surface of the table feeder disc, and the disc is driven from the same motive element which drives the blower and pulverizer. Thus as previously stated, the material and air are regulated 20 in accordance with the capacity of the pulverizer.

25 In the foregoing the novelty and utility of the invention has been pointed out and, in connection with the accompanying drawings forming a part of this specification, I shall now describe 30 a particular embodiment of the invention for the purpose only of making such a disclosure as is required by the patent statutes.

In the drawings:

30 Figure 1 is a side elevation of a pulverizer unit, partly in section and showing the table feeder; Fig. 2 is a top plan view thereof;

Fig. 3 is a vertical central section on the line 3—3 of Fig. 2;

Fig. 4 is a sectional view on the line 4—4 of 35 Fig. 3;

Fig. 5 is a sectional view on the line 5—5 of Fig. 3.

In the drawings a foundation plate 1 has secured thereto a stationary grinding ring 2 by any 40 suitable means, such, for instance, as welding, and the upper face 3 thereof is provided with a race 4 in which rolling elements 5, such as balls, may travel. The outer periphery 6 of the race 4 is annularly beveled outwardly, as shown, to assist 45 material to be pulverized in gravitating beneath and between the balls 5.

A central member 7 secured to the foundation plate 1 by a cap screw 8 may substantially close 50 the opening in the lower stationary grinding ring 2.

Above the stationary grinding ring 2, and in opposed relation to the race 4 thereof, and on top of the balls 5 which seat in its race 9 is a floating ring 10, the outer periphery of which 55 overhangs the balls 5 and carries scraper lugs or plows 11, while the inner opening is provided with lugs 12 which engage in loose driving relation with similarly arranged lugs 13 on a floating driving member 14; wearing plates 15 are bolted or 60 otherwise secured to either lugs 12 or 13.

The central portion of the driving connection 14 extends outwardly and carries four radial arms 16, at the outer end of each of which is an adjusting screw 17 with a lock nut 18, and the lower 65 end of each adjusting screw contacts with a socketed cap 19 bearing on the upper end of a spring 20 seated over a spring retaining member 21 on the upper side of the floating grinding ring 10. By adjusting the screw 17 the compression 70 of the spring 20 may be increased or decreased to exert a greater or lesser pressure upon the ring 10 and thereby regulate the grinding adjustment existing between the rings 2 and 10 and the balls 5.

75 The arms 16, at their center, engage with a

clutch member 22 having jaws 23 which enter cooperating spaces provided by the shape of the arms 16 and thereby engage the clutch member 22 and the member 14 in loose driving relation.

It is to be noted that by this arrangement the ring 10 has a floating action with respect to the member 14, and the member 14 has a floating action with respect to the clutch member 22 so that rocking of the elements with respect to each other during grinding operation is freely permitted without imposing any appreciable strain on the main driving mechanism to be hereinafter described.

Surrounding the grinding rings 2 and 10 is an annular member 24, the upper portion of which 15 is beveled outwardly as indicated at 25 to an angle corresponding with the face 6 of the race 4 of the lower grinding ring 2, and such beveled portion 25 therefore is adapted to receive and direct air and material between and among the balls 5.

This annular member 24 is surrounded in spaced relation by an outer casing 26 except that it contacts therewith along the upper edge. Inwardly of the casing 26 and in concentric relation therewith, is a skirt member 27 thus forming an air passage 28 between the casing 26 and said member 27 which delivers air downwardly onto the inclined surface 25 of the annular member 24, in a direction to sweep between the grinding rings 2 and 10 and among the balls 5. The lower end of this skirt 27 has slots 29 which are engaged by bolts 30 holding a drop ring 31 in position to be raised or lowered with respect to the inclined surface 25 either to increase or reduce the velocity of air entering the pulverizing zone.

An entrance opening is provided in the casing 26 and through the skirt 27, and is closed by a door 32 provided with handles 33, as shown, and suitably secured in place by the members 34 40 which are simply swing bolts 35 engaging in lugs 36 carried by the door.

Referring again to the driving mechanism, the clutch member 22 is carried upon the tapered end 37 of a shaft 38, and is additionally secured against rotation with respect to said shaft by the key 39, and is held on the end of the shaft by the disc 40 secured by the bolt or cap screw 41, the upper end of the member 14 being recessed as shown at 42 to accommodate said disc 40 and the head of the cap screw 41, the partition 43 being provided to prevent the cap screw 41 or disc 40 from dropping down into the lower part of the mechanism should it become loosened.

The casing 26, at the top, is closed by a cover plate 44 having outlets 45 therein to provide for the exit of the pulverized material. The cover plate 44 mounts a bevel gear housing 46 through the medium of supporting legs 47 secured to the cover plate 44 by cap screws 48. Said bevel gear housing 46 has a chamber 49 axially aligned with and receiving the shaft 38. A radial bearing 50 is in the lower end of the chamber 49 and acts to support the shaft 38, while the upper end of said shaft carries a bevel gear 51 keyed thereto as at 52, and the shaft 38 extends beyond the bevel gear and through a radial bearing 53 mounted in a cover plate 54 closing the gear housing 46 and an oil chamber 55 formed therein.

The upper end of the shaft 38, in connection with the cap member 54, carries a thrust bearing 56 which absorbs the grinding pressure, but it is to be noted that this grinding pressure is lessened by the fact that the driving parts and adjusting 75

mechanism exert their pressure, due to weight, in a downward direction.

The shaft 38 has an extension 57 through the top of the cap 54 which carries a small bevel gear 58 for purposes to be hereinafter described.

The oil chamber 55 is equipped with an oil level gauge 59, as shown, and with a filler plug 60. At the side of the bevel gear housing 46 is an extension 61 flanged as at 62 and bored out 10 to receive a cooperating bearing carrying member 63 provided with radial thrust bearings 64 and 65, the flange 62 being bolted to a flange 66 of the bearing carrying member 63 in any suitable manner, and the two bearings supporting 15 a pinion shaft 67 at the inner end of which is keyed, as at 68, a pinion 69 held on the shaft by a nut 70 and meshing with the bevel gear 51 to drive the shaft 38 when power is applied to the pinion shaft 67.

20 An oil sealing gland 71 surrounds the outer end of the shaft which is extended as at 72 and provided with a keyway 73 for the mounting of a pulley or sprocket 74 constituting a part of the drive, as will be hereinafter described.

25 Within the pressure chamber formed by the casing 26 and surrounding the shaft 38 below the radial bearing 50 is an annular drop well 75 having a transverse partition 76 provided with packing 77 and closing plate 78 bolted in place as 30 shown to seal the shaft 38. Immediately below the closing plate 78 is a partition 79 having bolted thereto a closing plate 80 extending inwardly to the shaft 38, but with no packing. The chamber thus formed will be hereinafter 35 referred to as the sealing pocket 81.

Adjacent the casing 26 is a positive pressure blower 82 having an air entrance 83 and an impeller 84 carried on the shaft extension 85 of a motor 86. The other end of the shaft carries 40 a driving pulley 87 which is belted or connected in driving relation by the element 88 to the pulley 74 for driving the pulverizer. The air outlet 89 of the blower is connected to the air inlet 90 of the casing 26 in such manner that the 45 air enters the annular space 28 tangentially and circulates around the annular space 28 with a swirling motion and is exhausted through the opening between the casing 26 and the adjustable member 31 of the skirt 27 inwardly in the 50 general direction of the inclined face of the annulus 24 adjacent the grinding elements, thus sweeping the fines into the air passing through the elements and up at the center and also around the outside thereof where they finally 55 leave the casing through the openings 45.

A connection 91 opening into the chamber 81 is brought into a position to receive the full velocity of the air leaving the blower and carries air to the chamber 81 where it has its velocity 60 component translated into a pressure component always greater than the pressure component in the chamber formed by the casing 26, and thus air continuously escapes between the shaft 38 and plate 80 thereby preventing any dust particles from reaching the interior of the casing 81 and consequently from reaching the sealing means 77 or the bearings of the shaft 38.

At the side of the casing 26 is a table feeding mechanism which comprises a casing 92 having 70 a partition 93 secured thereto and mounting a rotatable disc 94. The disc 94 has a shaft 95 which is provided with a gear 96 meshing with a pinion 97 for driving the disc or table 94. The shaft 95 is connected by a shaft 98 supported in 75 a bearing 99 with a shaft 100 by means of a uni-

versal joint 101. A second universal joint 102 connects the shaft 100 with a stub shaft 103 supported in the bearing 104. The shaft 103 carries a bevel gear 105 meshing with the bevel pinion 58 on the end of the shaft 38. Thus the motor 86 drives the pulverizer, the blower and the table feeder, the whole assembly forming a unitary apparatus.

An annulus 106 within the casing 92 and secured to the bracket 93 prevents material from 10 spilling beneath the table to any great extent. The annulus 106 carries guiding means 107 which guides the material discharged from the table through the opening 108 into the casing 28. From that location the material falls onto the beveled 15 surface 25 of the annular member 24 surrounding the grinding elements, thus entering between the grinding rings 2 and 10 and among the balls 5.

A journal 109 in the top of the casing 92 carries a shaft 110 which carries an arcuate vane or gate 112 within the casing and extending partly across the table 94. The gate 112 cooperates with a fixed curvilinear wall extending inwardly from the opposite side of the casing 92 at one 20 side of the entrance 108 to define a segmental material inlet section to which a supply connection 113 opens. The convex side of the fixed curvilinear wall is arranged in opposition to the direction of rotation of the table. The gate 112 25 when closed is arranged as shown in dotted lines in Fig. 1 and swings toward the casing wall to allow material on the table to pass through the opening formed between the gate and fixed curvilinear wall out of the material inlet section. 30 The fixed wall acts as a scraper to deflect material into the entrance 108. The upper end of the shaft 110 which carries the arcuate gate 112 extends outside of the casing 92 and carries a lever arm 114 connected with a second lever arm 115 35 which may be secured in any adjustable position by a rocking means 116, and through the medium of a lever 115 the gate or vane 112 may be positioned to any adjusted opening to regulate the feeding of the material.

On the top of the casing 92 are lugs 117 which secure an inspection plate 118 in place.

It will be seen from the foregoing that I have provided a top drive mill with a floating upper grinding ring, a floating connection between the 50 grinding ring and the driving mechanism, and a solid bottom ring, and that the parts are interconnected for driving purposes so that a single drive accomplishes the operation of all three elements, namely, the pulverizer, the blower and 55 the table feeder.

While in the foregoing I have set forth a specific form of the invention, it is nevertheless to be understood that in carrying the same into practice I may resort to any and all modifications falling within the scope of the appended claims defining my invention. In the claims, the term "air" is used generically to cover any gaseous carrier medium suitable for removing pulverized material in the manner described.

I claim:

1. A pulverizer including a stationary and a movable grinding ring in opposing relation, rolling grinding elements therebetween, driving mechanism for said movable grinding ring, a casing for the pulverizer and a concentric shell within said casing forming an annular peripheral entrance between said rings for introducing air and material to be pulverized, means for feeding air and material thereto, and means annu- 70 75 75

larly dividing the entrance between said rings and adjustable to regulate the air velocity in the zone adjacent the grinding elements.

2. An air-swept pulverizer comprising a casing having an outlet for material-laden air in its upper portion, a non-rotary bottom grinding ring, a circular row of rotary grinding elements supported on said bottom ring, a rotary top grinding ring supported on said grinding elements, a rotary spider having a floating drive connection with said top ring and a plurality of radial arms, a compression spring positioned between each of said radial arms and said top ring, an adjusting screw on each of said radial arms for adjusting the compression of the corresponding spring, a main drive shaft above and coaxial with said spider and extending through the top wall of said casing, means forming a clutch connection between said shaft and spider, means externally of said casing for driving said shaft, means for delivering material to be pulverized to the outer side of said row of grinding elements, and means causing a current of air to sweep up pulverized material and carry the same upwardly to said casing outlet.

3. An air-swept pulverizer comprising a casing having an outlet for material-laden air in its upper portion, a non-rotary bottom grinding ring, a circular row of rotary grinding elements supported on said bottom ring, a rotary top grinding ring supported on said grinding elements, a rotary spider having a floating drive connection with said top ring and a plurality of radial arms, a compression spring positioned between each of said radial arms and said top ring, an adjusting screw on each of said radial arms for adjusting the compression of the corresponding spring, a main drive shaft above and coaxial with said spider and extending through the top wall of said casing, means forming a clutch connection between said shaft and spider, means externally of said casing for driving said shaft, means for delivering material to be pulverized to the outer side of said row of grinding elements, openings in said top ring for the passage of material-laden air, and means causing a current of air to sweep up pulverized material and carry the same upwardly through the openings in said top ring to said casing outlet.

50 4. An air-swept pulverizer comprising a casing having an outlet for material-laden air in its upper portion, a non-rotary bottom grinding ring, a circular row of rotary grinding elements supported on said bottom ring, a rotary top grinding ring supported on said grinding elements, a rotary spider having a floating drive connection with said top ring and a plurality of radial arms, a compression spring positioned between each of said radial arms and said top ring, an adjusting screw on each of said radial arms for adjusting the compression of the corresponding spring, a main drive shaft above and coaxial with said spider and extending through the top wall of said casing, means forming a clutch connection between said shaft and spider, means externally of said casing for driving said shaft, means for delivering material to be pulverized to the outer side of said row of grinding elements, a plow mounted on said top ring at the outer side of said row of grinding elements, and means causing a current of air to sweep up pulverized material and carry the same upwardly to said casing outlet.

55 5. An air-swept pulverizer comprising a casing having an outlet for material-laden air in its top

wall, a non-rotary bottom grinding ring, a circular row of rotary grinding elements supported on said bottom ring, a rotary top grinding ring supported on said grinding elements, a rotary spider having a floating drive connection with said top ring and a plurality of radial arms, a compression spring positioned between each of said radial arms and said top ring, an adjusting screw on each of said radial arms for adjusting the compression of the corresponding spring, a main drive shaft above and coaxial with said spider and extending through the top wall of said casing, means forming a clutch connection between said shaft and spider, means externally of said casing for driving said shaft, means including an inclined baffle for delivering material to be pulverized to the outer side of said row of grinding elements, a plow mounted on said top ring at the outer side of said row of grinding elements, openings in said top ring for the passage of material-laden air, and means causing a current of air to sweep up pulverized material and carry the same upwardly through the openings in said top ring to said casing outlet.

6. A pulverizer comprising a bottom grinding ring, a circular row of rotary grinding elements supported on said bottom ring, a rotary top grinding ring supported on said grinding elements, a rotary spider having a plurality of arms, a compression spring positioned between each of said arms and said top ring, a drive shaft for said spider and top ring, means for delivering material to be pulverized to the outer side of said row of grinding elements, and means causing a current of air to sweep up pulverized material and carry the same upwardly within said row of grinding elements.

7. A pulverizer comprising a non-rotary bottom grinding ring, a circular row of rotary grinding elements supported on said bottom ring, a rotary top grinding ring supported on said grinding elements, a rotary spider having a plurality of arms, a compression spring positioned between each of said arms and said top ring, an adjusting screw on each of said arms for adjusting the compression of the corresponding spring, a main drive shaft above and coaxial with said spider, said drive shaft extending downwardly through the top wall of said casing with its lower end terminating above said row of grinding elements, and means for delivering material to be pulverized to one side of said row of grinding elements.

8. A pulverizer comprising a non-rotary bottom grinding ring, a circular row of rotary grinding elements supported on said bottom ring, a rotary top grinding ring supported on said grinding elements, a rotary spider having a drive connection with said top ring and a plurality of arms, a compression spring positioned between each of said arms and said top ring, an adjusting screw on each of said arms for adjusting the compression of the corresponding spring, a main drive shaft above and coaxial with said spider with its lower end terminating above said row of grinding elements, means forming a clutch connection between said shaft and spider, means for driving said shaft, and means for delivering material to be pulverized to one side of said row of grinding elements.

9. An air-swept pulverizer comprising a casing having an outlet for material-laden air in its upper portion, a bottom grinding ring, a circular row of rotary grinding elements supported on said bottom ring, a rotary top grinding ring sup-

ported on said grinding elements, a rotary spider having a plurality of arms, a compression spring positioned between each of said arms and said top ring, a drive shaft for said spider and top ring, means for delivering material to be pulverized to the outer side of said row of grinding elements, and means causing a current of air to sweep up pulverized material and carry the same upwardly through said top grinding ring to said 10 casing outlet.

10. An air-swept pulverizer comprising a casing having an outlet for material-laden air in its upper section, a bottom grinding ring, a circular row of rotary grinding elements supported 15 on said bottom ring, a rotary top grinding ring supported on said grinding elements, a rotary spider having a plurality of arms, a compression spring positioned between each of said arms and said top ring, a drive shaft for said spider and top ring, an opening formed in said top ring for the passage of material-laden air, means for delivering material to be pulverized to the outer side of said row of grinding elements, and means causing a current of air to sweep up pulverized 20 material and carry the same upwardly through said top ring opening to said casing outlet.

11. A pulverizer comprising a bottom grinding ring, a circular row of rotary grinding elements supported on said bottom ring, a rotary top

grinding ring supported on said grinding elements, a rotary spider having a plurality of arms, a compression spring positioned between each of said arms and said top ring, a drive shaft for said spider and top ring, means for delivering material to be pulverized to the outer side of said row of grinding elements, and a plow mounted 5 on said top ring at the outer side of said row of grinding elements.

12. An air-swept pulverizer comprising a casing having an outlet for material-laden air in its upper section, a bottom grinding ring, a circular row of rotary grinding elements supported on said bottom ring, a rotary top grinding ring supported on said grinding elements, a rotary 15 spider having a plurality of arms, a compression spring positioned between each of said arms and said top ring, a drive shaft for said spider and top ring, an opening formed in said top ring for the passage of material-laden air, means for 20 delivering material to be pulverized to the outer side of said row of grinding elements, a plow mounted on said top ring at the outer side of said row of grinding elements, and means causing a current of air to sweep up pulverized material 25 and carry the same upwardly through said top ring opening to said casing outlet.

RALPH M. HARDGROVE.
